UNITED STATES PATENT OFFICE.

WILLIAM H. OGDEN, OF BINGHAMTON, NEW YORK.

PACKING FOR ENGINES.

1,020,842.

Specification of Letters Patent. Patented Mar. 19, 1912.

Application filed November 24, 1911. Serial No. 662,232.

To all whom it may concern:

Be it known that I, WILLIAM H. OGDEN, a citizen of the United States, residing at Binghamton, in the county of Broome and State of New York, have invented a certain new and useful Improvement in Packings for Engines, Valves, and the Like, of which the following is a full, clear, and exact description.

The object of this invention is to provide means for rendering substantially fluid-tight the rotary elements, such as pistons, abutments, steam-chests or other fluid chests, valves, or other parts of steam engines, internal combustion engines, and other engines or machines, which parts are arranged within cylinders or casings and have their ends fitted against the heads or end walls of said cylinders or casings and require a substantially fluid-tight engagement between themselves and their cylinders or casings; said means being of such character as to be effective in operation and automatically maintain a balance between the friction and operative parts, and also insure a fluid-tight contact of parts, without any undue amount of friction or leakage, and compensate for expansion and wear between the parts.

The invention consists in a packing for devices of the character mentioned, comprising in one preferred form, a substantially cylindrical rotary member having its end or ends formed with a spiral surface, and a substantially circular packing plate having a reverse spiral surface arranged adjacent to and engaging the spiral surface of said rotary member, and a plane outer surface adapted to engage the adjacent wall of the casing for said rotary member, so that in the operation of the rotary member the co-action of the spiral surfaces will insure a fluid-tight contact of the packing plate with the adjacent wall of the inclosing member, all as I will proceed now more particularly to set forth and finally claim.

Without thereby restricting the scope and utility of the invention, I have herein shown the same as embodied in a rotary valve and one form of rotary engine.

In the accompanying drawings illustrating the invention, in the several figures of

which like parts are similarly designated, Figure 1 shows a valve with the rotary member and packing in elevation, and its casing in section. Fig. 2 is a perspective view of the rotary member of the valve of Fig. 1, and one of the packing plates detached. Fig. 3 is an elevation of an abutment for rotary engines with the invention applied thereto and showing a portion of the cylinder in section. Fig. 4 is an end elevation of the rotary abutment of Fig. 3. Fig. 5 is an elevation of the packing plate for the abutment of Figs. 3 and 4, showing the spiral surface thereof. Fig. 6 is an interior elevation of a trefoil or three cylinder rotary engine having a rotary abutment and steam or gas chest provided with my invention. Fig. 7 is a detail perspective view showing a modification. Fig. 8 is an edge view of the packing plate of Figs. 3, 4, 5 and 6.

Referring to Figs. 1 and 2, the rotary cylindrical body or member 1 of the valve has its ends formed or provided with a spiral surface 2, terminating in a shoulder or stop 3. This cylindrical body or member 1, may be fixedly mounted upon or made integral with a shaft 4 projecting a suitable distance beyond the end walls thereof to be mounted in bearings therefor in the heads or side walls 5 of a casing 6, said shaft being adapted to be connected with any suitable mechanism for continuously rotating said cylindrical body or member.

Loosely mounted upon the projecting ends of the shaft 4 within the casing are circular packing plates 7 having their inner faces formed or provided with spiral surfaces 8, complementary to the spiral surfaces of the body or member 1, and terminating in a shoulder or stop 9, said packing plate with its spiral surface fitting closely up against and engaging the spiral-surfaced ends of the body or member 1, with the shoulders or stops 3 and 9 thereof adjacent. A coiled or other spring 10 is fixed between the adjacent shoulders or stops 3 and 9, to keep said shoulders or stops slightly separated to permit of the operation of the packing plates as hereinafter described. The outer faces 11 of the packing plates are constructed as a plane surface to fit closely against the adjacent

surfaces of the walls of the casing heads 5, to form a fluid-tight contact therewith.

In Figs. 3, 4, 5, 6 and 8, I have shown the invention as applied to a combined rotary 5 abutment and steam or gas-compression chest such as is employed in the rotary steam engine forming the subject of my application for patent filed May 16, 1911, Serial No. 627,579, or in my internal combustion en- 10 gine forming the subject of my application for patent filed June 20, 1911, Serial No. 634,385. In this form of the device, the rotary abutment and steam or gas chest 12 is of volute form; and in accordance with this 15 invention the ends of the rotary abutment are formed or constructed with a spiral surface 13 beginning at the leading end 14 of the abutment and gradually increasing in depth toward the longitudinal center of the 20 abutment and terminating in a shoulder or stop 15, at the exhaust side of the abutment. The abutment is fixedly mounted upon a shaft or has trunnions made integral therewith, as indicated at 16, adapted to engage 25 suitable bearings therefor in the ends or heads 17 of the cylinder or casing 18.

Loosely mounted upon the shaft or trunnions 16, upon opposite sides of the abutment, are the packing plates 19 formed to 30 substantially correspond in outline to the volute ends of the abutment, and provided with the spiral surfaces 20, beginning at the leading end 21 of the plate very thin and gradually increasing in thickness on the in- 35 side adjacent to the ends of the abutment, to form said spiral surface, its radii being always at right angles to the vertical axis or hub of the abutment, and its greatest thickness being at the exhaust side of the abut- 40 ment, and terminating in a straight edge 22, extending substantially radially from the axis of the plate, and constituting a stop terminating at and arranged adjacent to the shoulder or stop 15 on the spiral-surfaced 45 end of the abutment. A coiled or other spring 23 is interposed between the stop or shoulder 15 and the stop 22, to keep the parts slightly separated to permit of the operation of the packing plates.

50 In Fig. 6 I have shown somewhat dia- grammatically in vertical section, a rotary engine such as that illustrated in my applica- tions for patents above mentioned, and in connection therewith have shown in eleva- 55 tion the combined abutment and fluid com- pression element constructed in accordance with this invention. In this form of the device the spiral packing plates are pro- vided with an elongated port or opening 24 to coöperate with the port in the fluid com- 60 pression element in maintaining an open port during the movements of the packing plates, although such movements are very slight. The outer faces 25 of the spiral

packing plates 19 are plane surfaces, and 65 are adapted to engage and maintain a fluid-tight surface contact with the heads of the cylinders during the movements of the moving parts.

The rotary members with this invention 70 applied thereto are arranged in their cylinders or casings so that the springs between the abutting stops or shoulders of the spiral surfaces on the ends of the body and the packing plates will tend to force the 75 packing plates forward in the direction of rotation of the rotary part; and during the operation of the device any friction between the packing plates and the heads of the cylinder or casing will force the packing plates 80 back against the pressure of the spring and thus automatically maintain a perfect balance of force between the friction and the spring and consequently a substantially per- 85 fect steam or gas-tight contact between the 90 rotary member and heads of the cylinder or casing is obtained, without undue friction or leak, and furthermore, the packing plates automatically accommodate them- 95 selves to and compensate for expansion or 100 contraction and wear. As only a very small fraction of an inch of variation is required for these conditions in any sized engine or machine, the movement of the spiral pack- 105 ing plate either forward or reversely would 110 be slight, thus not affecting materially the change in position of any ports that it may be necessary to provide in the packing plates. This, however, may be overcome by elongating the ports, as above described. 115 Should the fluid pressure find its way be- 120 tween the spiral surfaces or between the rotary member and cylinder heads, the spring would immediately force the spiral packing plate forward and close the space 125 and force out such steam or other pressure; and should the engine become heated and the parts expand, the friction between the 130 spiral packing plates and cylinder heads 135 would force the packing plates back and 140 thus compensate for such expansion and prevent undue friction between the parts.

In the application of the invention to the rotary engines of my applications herein- 145 before referred to, the spaces or openings between the stops and shoulders of the spiral surfaces being arranged on the exhaust side of the abutment and fluid compressing chest would in no wise affect the operation 150 of the engine by any leakage that might occur at this point. However, in other applica- 155 tions of the invention, it may be necessary to provide against leakage at the opening between the adjacent edges or stops of the spiral packing plate and rotary mem- 160 ber, and as one illustration of such provi- 165 sion, I have shown in Fig. 7 a rotary valve member 1, such as that shown in Figs.

1 and 2, provided with a lip or plate 26
overhanging the stop or shoulder 3 and fit-
ting and adapted to slide upon a counter-
sunk portion 27 of the spiral packing plate
5 7. Thus it will be seen that the opening be-
tween the adjacent edges of the rotary mem-
ber and its spiral packing plate at the sur-
face of the rotary member is always kept
10 closed irrespective of the movements of the
packing plate relative to the rotary mem-
ber.

I have herein shown the invention as ap-
plied to cylindrical rotary or revolving de-
vices, but I wish it to be understood that the
15 invention is not limited to such use, as it
is equally applicable to any revolving or
rotary member requiring end-packing
against a casing or cylinder head, whether
20 said rotary or revolving member be cylin-
drical or tapering.

Furthermore, I do not wish to be under-
stood as limiting the invention to the exact
25 details of construction herein shown and
described, as the same may be changed in
various particulars without altering the
scope of the invention.

What I claim is:—

1. The combination of a rotary member
provided with a spiral-surfaced end, a cas-
30 ing therefor, and a packing plate loosely
mounted upon said rotary member and hav-
ing a complementary spiral surface in con-
tact with the spiral-surfaced end of said
35 rotary member and a plane surface in con-
tact with the adjacent wall of said casing.

2. A packing, comprising a rotary mem-
ber and a casing therefor, said rotary mem-
ber provided with a spiral-surfaced end
40 terminating in a shoulder, a packing plate
loosely mounted upon said rotary member
and having a complementary spiral surface
contacting with the spiral-surfaced end of
the rotary member and terminating in a
45 shoulder adjacent to the shoulder on the
rotary member and a plane surface contact-
ing with the wall of said casing, and a
spring interposed between said shoulders
50 for forcing said packing plate in the direc-
tion of rotation of said rotary member and
maintaining a yielding contact between said
packing plate and the wall of the casing.

3. A packing, comprising a cylindrical ro-
tary member, a shaft therefor, and a casing
55 in which said member is mounted, said cy-
lindrical rotary member having its opposite
ends provided with spiral surfaces terminat-
ing in shoulders, packing plates loosely
60 mounted upon said shaft at the ends of said
rotary member and having complementary
spiral surfaces adjacent to the spiral sur-
faces of said ends and terminating in shoul-
ders adjacent to the shoulders on said rotary
65 member, and plane outer surfaces to con-
tact with the walls of said casing, and

springs interposed between said shoulders to
force said spiral-surfaced packing plates in
the direction of rotation of the rotary mem-
ber and maintain a yielding contact between
70 said packing plates and the walls of the
casing.

4. In a rotary engine, the combination
with the cylinder and pistons thereof, of a
rotary abutment for said pistons, having
spiral surfaces, a supporting shaft, and
packing plates loosely and yieldingly mount-
75 ed upon said shaft adjacent to said spiral
surfaces and having complementary spiral
surfaces in movable contact with the spiral
surfaces first named, and plane outer sur-
faces yieldingly contacting with the inner
80 walls of the cylinder.

5. In a rotary engine, the combination
with the cylinder and pistons thereof, of a
combined abutment and compression chest,
comprising a rotary member of volute form
85 having spiral-surfaced ends, a shaft upon
which said rotary member is mounted in
said cylinder, and volute packing plates
loosely and yieldingly mounted upon said
shaft and having complementary spiral sur-
90 faces adapted to contact with the spiral-
surfaced ends of said rotary member, and
plane outer surfaces adapted to yieldingly
contact with the inner walls of the cylinder
heads.

6. In a rotary engine, the combination
with the cylinder and pistons thereof, of a
combined abutment and compression chest,
comprising a volute rotary member having
100 spiral-surfaced ends terminating in shoul-
ders, a shaft upon which said rotary member
is mounted in said cylinder, volute pack-
ing plates loosely mounted upon said shaft
and having complementary spiral surfaces
105 adapted to contact with the spiral-surfaced
ends of said rotary member and terminating
in stops adjacent to the shoulders on said
rotary member and plane surfaces to con-
tact with the inner walls of said cylinder,
110 and springs interposed between said shoul-
ders and stops to force said packing plates
in the direction of rotation of said rotary
member and thereby maintain said packing
plates in yielding contact with the walls of
115 the cylinder.

7. A packing, comprising a cylindrical ro-
tary member, a shaft therefor, and a casing
in which said rotary member is mounted,
said cylindrical rotary member having its
opposite ends provided with spiral surfaces
120 terminating in shoulders, packing plates
loosely mounted upon said shaft at the ends of said
rotary member and having complementary
spiral surfaces adjacent to the spiral sur-
faces of said ends and terminating in shoul-
ders adjacent to the shoulders on said rotary
member and plane outer surfaces to
125 contact with the walls of said casing, springs

interposed between said shoulders to force
said packing plates in the direction of rota-
tion of said rotary member and maintain a
yielding contact between said packing plates
5 and the walls of the casing, and a plate car-
ried by one of said members and overhang-
ing the opening between said shoulders and
slidably engaging the other member.

In testimony whereof I have hereunto set
my hand this 23 day of November A. D. 10
1911.

WILLIAM H. OGDEN.
